UNITED STATES PATENT OFFICE.

KATSUJIRO SANWO, OF FRESNO, CALIFORNIA.

TRAY-PILEING MACHINE.

1,342,463.

Specification of Letters Patent. Patented June 8, 1920.

Application filed May 6, 1919. Serial No. 295,249.

To all whom it may concern:

Be it known that I, KATSUJIRO SANWO, a subject of the Emperor of Japan, residing at Fresno, in the county of Fresno and 5 State of California, have invented a new and useful Tray-Piling Machine, of which the following is a specification.

This invention relates to a new and useful machine adapted for piling fruit trays, 10 particularly for piling trays employed for drying grapes and for harvesting similar fruit.

The present method of handling grapes consists in gathering the grapes on small 15 trays which are placed in a row, and afterward gathering the trays separately and placing the same upon a vehicle for transportation.

The objects of this invention are to facilitate the harvesting of the grapes, and to 20 attain this end, I have provided a machine adapted to gather the trays from a row, pile the trays upon one another until a convenient pile is obtained, and to deposit the pile 25 of trays upon the ground.

Upon the annexed drawings, Figure 1 is a top plan view of a machine embodying my 30 invention. Fig. 2 is a side elevation of the same. Fig. 3 is a fragmentary detail view showing the method of tripping the conveyer. Fig. 4 is a rear elevation of the machine. Fig. 5 is a fragmentary and perspective view of the operative parts showing 35 the gear drive therefor. Fig. 6 is a fragmentary detail view of the same. Fig. 7 is a fragmentary detail view of the clutch transmission. Fig. 8 is a fragmentary and top plan view of the operative parts.

Referring to the drawings, my invention 40 consists of a frame 11, having the front frame member 12, side frame members 13 and 14, and transverse frame members 15 and 16. Frame member 16 is connected to frame members 13 beneath the main axle 17. 45 The main shaft 17 is journaled in bearing members 18 and 19, respectively, mounted on and projecting from frame members 13 and 14, on one side of the machine, and in bearing members 20 and 21, respectively, secured to the inner side of frame members 13. 50 The main wheel 22 is mounted on and rotates with the main shaft 17. The wheel 23 is journaled in bearings 24 and 25, respectively, projecting upward from frame members 13 and 14, on the opposite side of the machine.

An auxiliary frame 26 is pivotally connected to brackets 27 projecting from transverse frame member 15. The forward end 28 is supported by truck wheels 29, and is 60 provided with extensions 30, working in slots 31, in the depending frame members 32. Springs 33 are interposed between the inner ends 34 of slots 31 and blocks 35 mounted on extensions 30. The auxiliary frame 65 may therefore tilt laterally to accord with inequalities of the ground. A bar 36 is swivelly connected to frame member 12, and may be secured in position on either side of the machine by passing the bolt 37 through 70 the bar 36 and extension 38. A whiffletree 39 is pivotally connected to the end of bar 36, and is adapted for connection with the traces of a harness. The driver's seat 40 is hooked over the grooved extension 41 forming the extremities of transverse bar 15, and may be placed on either side of the machine in accordance with the position of the whiffletree. 75

The auxiliary frame 26 has mounted 80 thereon the platform 42, over which the trays pass as they are taken from the ground. The forwardly extending teeth 43, having rounded extremities 44, pass upon the surface of the ground and engage with the 85 trays which pass over the platform 42 upon forward motion of the machine. Inclined guides 45 force the trays to engage with the conveyer belts 46, whence the trays are conveyed to the rear portion of the machine. 90

The endless conveyer belts 46, are provided with a series of carriers 47, pivotally connected to lugs 48, and formed with projecting extremities 49 upon which the trays ride as they are conveyed to the rear of the machine. 95 The carriers ride upon the platform 42 until approaching the rearward limit of travel, when the weight of the trays serves to keep the carriers in position. The integral lugs 50 counterbalance the extremities 49 and 100 serve to maintain the carriers in position when the trays are removed. The conveyer belts 46 are actuated by pulleys 51 which are provided with teeth 52, engaging with corresponding holes 53 in the belts. Through 105 gears 54 and 55, countershaft 56, gears 57 and 58, and the vertical shafts 59, motion is transmitted from the main shaft 17 to the pulleys 51, the ratio of gearing being such that the speed of the conveyer belts is 110 slightly greater than the speed of the periphery of the master-wheel 22.

Vertically disposed conveyer belts 60, are provided with horizontally arranged carriers 61, which are adapted to receive the trays from the conveyer belts 46. Rotary 5 tripping members 62, adapted to engage with lugs 50 on carriers 47, will release the trays from conveyers 47, the trays dropping upon carriers 61. A guide member 92 serves to retain the trays upon the stacking carriers, and is provided with a cam member 93, adapted to engage with the inoperative carrier when the lowermost operative carrier approaches the delivery position, thereby moving the guide to the inoperative position.

The conveyer belts 60 are actuated by sprocket gears 63, mounted on shafts 64, which, through gears 65 and 66, are driven by the countershaft 67. The gears 68, on shafts 64, are in mesh with pinions 69, on shafts 70. The rotary tripping members 62 are fixed to shafts 70, and the ratio of gearing between gears 68 and pinions 69 is such that the tripping members make a half revolution during one-sixth of a revolution of the sprocket gears 63. The carriers 61 therefore advance downward the depth of one tray as the tripping members are actuated.

30 The gear 71 is fixed to the master-wheel 22 and drives the pinion 72, shown in Figs. 7 and 8. The pinion 72 drives the clutch member 73, journaled in the bearing member 18. A corresponding ratchet clutch member 74, having an integral sleeve 75, is slidingly mounted on a countershaft 76. A spring 77, interposed between the bearing member 78 and the flanged end 79, of sleeve 75, tends to shift the clutch member 74 into engagement with clutch member 73. A gear-wheel 80, on shaft 67, is in mesh with a pinion 81, fixed to shaft 76, provided with a key member 82, whereby the clutch sleeve 75 and countershaft 76 will rotate simultaneously. The gear ratio between gear-wheel 80 and pinion 81, and bevel-gears 65 and 66, is such that the clutch members 73 and 74 and the countershaft 76, make one revolution during one-sixth of a revolution of sprocket gears 63. The carriers 61 therefore advance downward the depth of one tray during one revolution of the clutch members. The clutch member 74 is provided with a projecting lug 83, adapted to engage with the pawl 84, pivotally mounted on a lug fixed to the bearing member 18. The pawl 84 is provided with an integral lever arm 85 and with an inclined cam face 86. When the pawl 84 is in operative position, the cam 86 engages with the lug 83, and serves to disengage clutch members 73 and 74. A rectangular link 87, pivotally connected to lever arm 85, and to swinging levers 88, is provided with a stop 89, secured 65 by the clamp 90, and adapted to be actuated

by the trays moving upon the carrier belts 46. The stop 89 may be adjusted so that as the trays approach the release position, the pawl 84 is actuated to release the clutch member 74, which is thereupon forced into 70 engagement with clutch member 73. Upon release of the tray, the spring 91 retracts levers 88 and 85, thereby placing the pawl 84 in operative position.

As the carriers 61 approach the limit of 75 their downward movement, the pile of trays will be released, and are deposited upon the ground. The ratio of gears is such that the tray releasing mechanism is actuated during a tenth part of a revolution of the master-wheel, but may be varied by employing a different ratio of gearing. The device may be operated by placing the driver's seat and tractor means on either side of the machine. The operation of 80 gathering the trays from the ground, conveying the same to the stacking mechanism, operating the stacking mechanism in accordance with the release of the trays from the conveying means, and the final delivery of the stack of trays upon the ground is automatically accomplished with the advancing movement of the machine.

From the foregoing description it will be seen that simple and efficient means are herein provided for accomplishing the objects of the invention, but while the elements shown and described are well adapted to serve the purposes for which they are intended, it is to be understood that the invention is not limited to the precise construction as set forth, but includes within its purview such alterations, changes, and modifications as may be made within the scope of the appended claims.

What is claimed is:

1. In a tray-piling machine, the combination with a frame, of a master-wheel and auxiliary wheel supporting the frame, an inclined frame pivotally connected to the main frame, truck wheels supporting the inclined frame, a pair of conveyer belts arranged to travel from the front end of the inclined frame to the rear of the main frame, tiltable carriers mounted on the conveyer belts and arranged in opposed relation to each other, means for operating the conveyer belts, means for tripping the carriers, vertical conveyer belts disposed at the rear of the machine, carriers on the vertical conveyer belts adapted to receive the trays from the first-named conveyer belts, means for operating the horizontal carriers with a downward step by step movement, and a stop operated by the trays as they approach the limit of their rearward movement, and arranged to control the actuating means for the stacking carriers and tripping means for the conveyers.

2. In a tray-piling machine, the combina- 130

tion with a main-frame and master-wheel and auxiliary wheel supporting the frame, of an inclined frame disposed in advance of the main-frame, conveyers including tilttable carriers moving upon the inclined frame and over the main-frame, guides on the inclined frame serving to move the trays into engagement with the conveyers, means operative upon rotation of the master-wheel 5
 10 for constantly actuating the conveyers, stacking elements disposed in the main-frame beneath the conveyers and including rotary sprockets, chain belts and carriers thereon, a train of gears serving to transmit motion from the master-wheel to the sprockets and chain belts, a clutch disposed in the chain of gears, a pawl having an inclined face normally holding the clutch in disengaged position, a reciprocatory link 15
 20 connected to the pawl, a stop depending therefrom and engaging with the trays as they approach the limit of their rearward travel, and operating the pawl to release the clutch, a cam on the clutch engaging with the inclined face on the pawl and serving to disengage the clutch at the completion of a revolution thereof, and a rotary tripping member for the conveyer carriers intermittently actuated upon movement of the stacking 25
 30 elements.

3. In a tray-piling machine, the combination with a frame and wheels supporting the frame, of conveyer means arranged to gather the trays consecutively from the ground, tilttable carriers mounted in the conveyer means, accumulative and stacking elements disposed beneath the tilttable carriers, a train of gears operative upon motion of the wheels to actuate the conveyer 35
 40 means and accumulative and stacking elements, clutch and gear elements for intermittently actuating the stacking elements during the movement of the conveyer means, rotary tripping elements for the tilttable carriers operated by the movement of the stacking elements, a spring tending to force the clutch elements into co-operative engagement, a pawl normally holding the clutch elements in inoperative position, and releasing means for the pawl actuated by engagement with the trays upon the conveyer 45
 50 means.

4. In a tray-piling machine, the combination with belt conveyers arranged to gather the trays from the ground and to move them to release position, of vertically movable

carriers mounted at the rear of the machine and disposed beneath the belt conveyers, gear and clutch means connecting the carrier elements with the main shaft, a master-wheel 60 to drive the main shaft, means for holding the clutch elements normally in inoperative position, and releasing means for the clutch retaining means, operated by engagement with the trays as they approach the release 65 position.

5 In a device as described, the combination with a pair of conveyers arranged to move the trays from the ground to release position, of carriers pivotally connected to 70 the conveyers at intervals thereon, stacking carriers disposed beneath the release position of the conveyers, means for operating the stacking carriers with a step by step intermittent downward movement, a guide 75 member to retain the trays upon the stacking carriers, a cam member on the guide retaining member actuated by the inoperative stacking carrier as the operative carrier approaches the delivery position, rotary tripping members for actuating the tilttable carriers on the conveyers, means for operating the rotary tripping members simultaneously with the intermittent downward movement of the stacking carriers, a master-wheel, a 80 gear-wheel fixed to the master-wheel and rotating therewith, a pinion driven by the gear-wheel, a clutch member rotating synchronously with the pinion, a corresponding ratchet clutch member, a shaft driven by the 85 ratchet clutch member, a train of gears whereby the countershaft drives the conveyers having the stacking carriers thereon, a cam on one of the clutch members, a pawl adapted to engage with the cam on the 90 clutch member, an inclined cam face on the pawl whereby the clutch members are thrown to disengaged position as the clutch members complete a revolution, a reciprocating frame to operate the pawl to inoperative 95 position, a stop carried by the reciprocating frame and operated by the trays as they approach the release position, and a spring to retract the reciprocating frame and pawl to the operative position upon delivery of the trays from the conveyer to the stacking carriers, and means for operating the conveyers independent of the operation of the stacking carriers.

In testimony whereof I hereunto affix my 110
 signature.

KATSUJIRO SANWO.
